(57) **CLAIM**

The ornamental design for a bottomless dump bag, as shown and described.

DESCRIPTION

FIG. 1 is an isometric view of the claimed bottomless dump bag in an engaged configuration, embodying the present design;

FIG. 2 is an isometric view of the claimed bottomless dump bag in a disengaged configuration, embodying the present design;

FIG. 3 is a front side view thereof, in an engaged configuration;

FIG. 4 is a rear side view thereof;

FIG. 5 is a right side view thereof;

FIG. 6 is a left side view thereof;

FIG. 7 is a top down plan view thereof; and,

FIG. 8 is a bottom up plan view thereof.

1 Claim, 8 Drawing Sheets(56)
